UNITED STATES PATENT OFFICE.

WILLIAM BATE, OF HAYLE, AND FREDERICK G. ORME, OF LONDON,
ENGLAND.

CONDENSER FOR NITRIC OR OTHER ACIDS.

SPECIFICATION forming part of Letters Patent No. 733,452, dated July 14, 1903.

Application filed December 6, 1902. Serial No. 134,142. (No model.)

To all whom it may concern:

Be it known that we, WILLIAM BATE, residing at Upton Villa, Hayle, Cornwall, and FREDERICK GEORGE ORME, residing at 11 5 Austin Friars, London, England, subjects of the King of Great Britain, have invented new and useful Improvements in Condensers for Nitric or other Acids, of which the following is a specification.

10 Our invention relates to condensers for nitric and other acids in which the acid vapor is constrained to pass up and down a stack of vertical pipes set in a tank of water or merely exposed to the air; and the objects of 15 our invention are to insure a thorough circulation of the condensing-water, to condense the acid vapors with a minimum quantity of water, to avoid as far as possible reducing the strength of the acid in the receiver should a 20 pipe crack or leak while a charge is being worked off, and to enable a defective pipe to be replaced by a sound one without interfering with the other pipes in the condenser. We attain these objects by the apparatus 25 illustrated in the accompanying drawings, in which—

Figure 1 represents front elevation, partly in section, of a condenser for nitric and other acids constructed according to this invention. 30 Fig. 2 is a plan of same with part of the wood frame removed. Fig. 3 is a section of condenser on line A B, Fig. 1. Fig. 4 is a vertical section, to an enlarged scale, of a portion of a condensing-pipe and water-jacket, showing method of making the joint between the pipe and the jacket. Fig. 5 is horizontal section of same on line C D, Fig. 4. Fig. 6 is 35 plan of gland-ring. Fig. 7 is plan of joint-ring. Fig. 8 is section of same. Fig. 9 is section showing alternative method of making the joint at the bottom of the water-jacket.

The same letters denote the same parts in all the figures.

Now according to this invention we make 45 the condenser of a stack of earthenware,

stoneware, or other suitable pipes *a*, arranged vertically in a wooden frame, the said pipes being connected together in pairs at the top by means of bends *b*. *c c* are pipes leading to the said receiver. These pipes are provided with sockets *d* to receive the lower ends of the pipes *a* and also with diaphragms *v* and by-passes *w* to compel the acid vapor to pass up and down the pipes *a* in its passage through the condenser. The bends *b* and 50 pipes *a* are jointed air-tight to their respective sockets by means of cement, clay, or other suitable material to prevent escape of vapor. In the drawings the stack of pipes consists of two rows of pipes containing five 55 pipes in each row; but a greater or less number of pipes may be used, so as to obtain the best results. The pipes *a* are recessed half-way into the portion *e* of the frame and are kept in position by lead collars *x*, screwed or 60 bolted to the frame, as shown by Figs. 1 and 3. The lower ends of the pipes *a* pass through apertures in the portion *f* of the framework. The portion *f* of the framework is covered with sheet-lead *g*, as shown by Figs. 4 and 9, 65 on both sides the said covering, being continued through apertures in the portion *f* to prevent the acid from coming in contact with the wood in case of leakage.

Surrounding six of the pipes *a* are open- 70 topped cylindrical water-jackets *h*, made of lead and fused at the bottom to the lead *g*, as shown in detail by Fig. 4, to make a watertight joint. The bottom of the said jacket is formed, as shown in detail by Fig. 4, by the 75 gland-ring *k* and an india-rubber joint-ring *l*, circular in section, as shown by Figs. 7 and 8, which ring is placed on the tube *a* and forced into contact therewith and with the bell-mouth *j* by means of the gland-ring *k* 80 and bolts *l*. A sufficient number of bolts are used to prevent the ring *l* from spreading outward. Instead of the rings *k* and bell-mouths *j*, ordinary glands may be used, stuffing-boxes being formed in the portion of the 85 90

frame by recesses cut into the wood into which the lead *g* is dressed, as shown by Fig. 9. The bolts *l* may be recessed into the wood *f* under the lead *g*, the said bolts being preferably furnished with square heads to prevent them from rotating. Each water-jacket is provided with three pipes—namely, an inlet-pipe for the condensing-water, an overflow-pipe for the same, and a drain-pipe for emptying the jacket.

n is the water-supply pipe to convey the condensing-water to the jackets *h*, each jacket communicating with the pipe *n* by means of a pipe and valve or stop-cock. The inlet-pipes to the jackets are fitted to the same near the bottom of the jackets. On the drawings the inlet-valves are marked *o*, the pipes connecting the water-jackets of the front row of pipes to the valves *o* are marked *p*, the inlet-pipes to the rear row of jackets being marked *q*. The overflow-pipes are fitted to the jackets as near the top as possible, as shown, the overflow-pipes from the front row of jackets being marked *r*, while the overflow-pipes from the rear row of jackets are marked *s*. The cold water, under a sufficient head to insure good circulation, enters the jackets near the bottom through the pipes *p* *q* and the warm water runs out at or near the top of the jackets down the pipes *r* *s* into a suitable gutter or drain, the amount of water passing through the jackets being regulated by the valves *o*.

t *t* are drain-pipes to run off the water from the front row of jackets when it is necessary to empty the same. *u* *u* are similar drain-pipes to empty the rear row of jackets. The drain-pipes are fitted as near the bottom of the jackets as possible.

The bottom of the drain-pipes *t* *u* are normally closed by plugs or bungs inserted therein, or instead of the plugs or bungs valves or cocks may be fitted to the drain-pipes.

All the pipes *p* *q* *r* *s* *t* *u* are made of lead and fused to the jackets *a*; but, if desired, iron pipes fitted with lead flanges may be used.

By incasing each pipe in a separate jacket less condensing-water is required and a more perfect circulation thereof obtained than when all the pipes are incased in a tank common to all. In the event of a pipe breaking, it is only necessary to empty the jacket, remove the bend connecting the broken pipe to the next pipe, remove the lead collar, take out the broken pipe, put a sound one in its place, replace lead collar and joint up, then screw up gland-ring, all of which can be done without in any way disturbing any of the remaining pipes. The joint-ring *i* and gland-ring *k* are slipped over the end of the new pipe while being lowered into place. In the event of a

pipe cracking while a charge is being worked off the water is at once shut off from the jacket of the cracked pipe, the plug or bung removed from the drain-pipe and the jacket emptied, thus preventing weakening of the acid in the receiver by water leaking through the crack, sufficient condensing-surface being left to finish off the charge if done carefully. If necessary, the top of the empty jacket may be stopped with clay to prevent escape of vapor.

The circular section india - rubber joint-rings we employ make a perfect joint without undue pressure on the earthenware pipes, thus avoiding risk of breaking the pipes when screwing up the glands, even if the said pipes are not truly circular.

The jackets should be emptied from time to time to clear away any mud or sediment that may accumulate therein.

If necessary, every condensing - pipe may be fitted with a water-jacket, but we find in practice that six jacketed pipes in a ten-pipe battery are quite sufficient for condensing nitric acid.

What we claim as our invention, and desire to secure by Letters Patent, is—

1. In a condenser for nitric and other acids of the vertical water-cooled type, the combination with vertical condensing-pipes of an independent open - topped water-jacket around each of said water-cooled pipes, and means for supplying water to, and emptying each jacket independently of the other jackets as specified, and for the purpose stated.

2. In a condenser for nitric and other acids of the vertical water-cooled type the combination with vertical condensing-pipes of an independent open - topped water-jacket around each pipe, a water-supply pipe, an overflow-pipe and a drain-pipe attached to each jacket, each supply-pipe, overflow-pipe and drain-pipe being independent of the supply-pipes, overflow-pipes and drain-pipes attached to the other jackets, means for regulating the supply of water to each jacket, and means for emptying any one jacket while leaving the other jackets full as specified and for the purpose stated.

3. In a condenser for nitric and other acids, the combination of a vertical pipe *a*, a cylinder of lead *h* fused at the bottom to the lead-covering *g* of the portion *f* of the frame of the apparatus, a gland-ring *k* and packing-ring *i* adapted to be forced into contact with the pipe *a* and with a bell-mouth *j* formed in the portion *f* of the frame by means of bolts *l* so as to form with the cylinder *h* a water-jacket surrounding the pipe *a* all substantially as set forth.

4. In a condenser for nitric and other acids, the combination of a pipe *a* recessed into the

portion *e* of the framework of the apparatus, a lead collar *x* screwed or bolted to the portion *e* to retain pipe *a* in position, a stuffing-box formed in portion *f* of the frame, a lead covering *g* for portion of frame *f*, a lead jacket *h* surrounding pipe *a* and fused to lead covering *g*, a gland-ring *k* and joint-ring *i* to form bottom of jacket, an inlet-valve *o* and pipe to admit cooling-water to jacket, an overflow-pipe to allow warm water to run off from jacket and a drain-pipe to empty jacket, all substantially as set forth.

In testimony whereof we have signed our

names to this specification in the presence of two subscribing witnesses.
